[57] CLAIM

The ornamental design for a tool caddy for a vacuum cleaner, as shown and described.

DESCRIPTION

FIG. 1 is a perspective view of the tool caddy, for a vacuum cleaner showing our new design with the tool caddy being shown in a closed position;

FIG. 2 is a perspective view of the tool caddy of FIG. 1 shown in an open position;

FIG. 3 is a front elevational view thereof;

FIG. 4 is a right side elevational view thereof;

FIG. 5 is a rear elevational view thereof; and;

FIG. 6 is a left side elevational view thereof;

FIG. 7 is a top plan view thereof; and,

FIG. 8 is a bottom plan view thereof.

The parts shown in broken lines in FIGS. 1 and 2 are shown for illustrative purposes only and form no part of the claimed design.
